UNITED STATES PATENT OFFICE

111,698

DESIGN FOR AN ELECTROLABRUM TREE

John L. Engstrom, Evanston, Ill.

Application July 18, 1938, Serial No. 78,562

Term of patent 14 years

To all whom it may concern:

Be it known that I, John L. Engstrom, a citizen of the United States, residing at Evanston, in the county of Cook and State of Illinois, have invented a new, original, and ornamental Design for an Electrolabrum Tree, of which the following is a specification, reference being had to the accompanying drawing, forming a part thereof.

Fig. 1 is a front elevation of an electrolabrum tree showing my new design;

Fig. 2 is a plan view thereof; and

Fig. 3 is a plan section taken on the line 3—3 of Fig. 1.

I claim:

The ornamental design for an electrolabrum tree as shown.

JOHN L. ENGSTROM.
